CLAIM

The ornamental design for an interrupter switch, as shown and described.

DESCRIPTION

FIG. 1 is a perspective view of an interrupter switch in the open position showing my new design;

FIG. 2 is a front elevational view of an interrupter switch in the closed position showing my new design;

FIG. 3 is a rear elevational view thereof;

FIG. 4 is a left side elevational view thereof;

FIG. 5 is a right side elevational view thereof;

FIG. 6 is a top-plan view thereof;

FIG. 7 is a bottom plan view thereof;

FIG. 8 is a rear elevational view of an interrupter switch showing a second embodiment of my new design, the difference being in the appearance of the insulators. All other aspects of the second embodiment are the same as those shown in FIGS. 1 and 7;

FIG. 9 is a left side elevational view thereof;

FIG. 10 is a right side elevational view thereof; and

FIG. 11 is a top plan view thereof.
